Primary Examiner—Lucy Lieberman

(57) **CLAIM**

The ornamental design for watch face, as shown and described.

DESCRIPTION

FIG. 1 is a perspective view of a watch face showing my new design; and,

FIG. 2 is a top plan view thereof.

The broken lines in the drawings are for illustrative purposes only and do not form part of the claimed design.

1 Claim, 2 Drawing Sheets

FIG. 1

FIG. 2
